STRAIGHT LIFT PUMPING APPARATUS

George T. Humphrey, Dallas, Tex.

Application April 26, 1937, Serial No. 138,881

10 Claims. (Cl. 74—103)

This invention relates to well pumping equipment and it has particular reference to pumping units for actuating the pump rod assembly in a well.

5 The principal object of the invention is to provide a pumping unit whereby a straight lift on the rod assembly is effected, thereby greatly reducing wear on the stuffing box packing, as well as minimizing the likelihood of breakage of the latter, since lateral stresses are not imposed on the polished rod as is the case when conventional equipment is used.

10 Another object of the invention is to provide a pumping unit so arranged that the walking beam thereof may be readily moved to a position such that no portion of the beam is directly over the casing head, thereby greatly facilitating the servicing of the well.

15 Another object of the invention is to provide a pumping unit wherein the conventional Samson post is replaced by a tripod frame, the latter being comprised of a hinged and articulated support and a pair of hinged and interconnected supports.

20 Still another object of the invention is to provide a pumping mechanism having a straight lift and which may be actuated from a point remote from the well.

25 With the foregoing objects as paramount, the invention has particular reference to its salient features of construction and arrangement of parts, which will become manifest as the description proceeds, taken in connection with the accompanying drawings, wherein:

30 Figure 1 is a side elevation of the pumping unit.
Figure 2 is a front elevational view.

35 Figure 3 is a fragmentary perspective view of the support for the articulated frame member.

40 Figure 4 is a perspective view of the bearing arrangement for the tripod members.

45 Figure 5 is a fragmentary perspective view of a base member, showing the slots therein for adjustment of the beam supports.

50 Figure 6 is an elevational view with portions broken away and showing the position of the beam and its supports at the upper end of the stroke.

55 Figure 7 is a front view in vertical section of the suspension bearing, showing its adaptation as a beam supporting means.

Figure 8 is a side elevation of Figure 7, shown partly in section.

Figure 9 is a perspective view of a fragment of the walking beam, and showing the attachment of the bearing thereto, and

Figure 10 is a side elevation of a modified form of the invention, showing its adaptation as a pump jack.

Referring primarily to Figures 1 and 2, 1 denotes the base members of the pumping unit which are preferably comprised of I beams spaced apart by a series of cross members 2. The base members 1 are slotted at 4 to allow for adjustment of the bearings 3. These bearings receive the ends of a shaft 4 to which a pair of beam supports 5 are rigidly attached. The supports 5 are thus seen to be free to rock, and the shaft 4, to which they are attached, is free to oscillate within the bearings 3. A pair of plates 6, formed as shown in Figure 2, are welded or otherwise secured to the uprights 5.

A lower journal member 7 is welded to the upper end of each of the supports 5, and a companion upper journal member 8 is bolted to each of the lower members 7. A shaft 9 is rigidly mounted between the journal members 7 and 8.

A walking beam 10 has a pair of bearing blocks 11, bolted thereto as shown in Figure 9. These blocks enclose a bushing 12 which surrounds the shaft 9. The walking beam 9 is thus seen to be free to rock on the shaft 9, which latter is rigid with respect to the uprights 5.

A shaft support 13 is secured to the forward end of each of the members 1. These supports serve to position a shaft 14, which shaft is held in place by set screws 15. A support 16, best shown in Figure 3, is comprised of a base 17, integral arms 18 and a depending portion 19. The base 17 of the member 16 serves to enclose the portion of the shaft 14 which is intermediate the supports 13, and the depending portion 19 is normally bolted to the cross members 2 by bolts 20.

A shaft 21 is secured in the arms 18 by set screws 22. The forward ends of the arms 18 are each provided with a lug 23, over which a section of pipe can be placed preparatory to swinging the walking beam to a position such that the well may be serviced.

The forward or articulated portion of the tripod support is comprised primarily of a link 24 and a pair of angular members 25, which latter are positioned on either side of the beam 24 and are rigidly secured to the walking beam 10. The lower end of the link 24 is provided with a bearing 26, shown in Figure 2, and the upper end of the link 24 is similarly provided with a bearing 27, attached as shown in Figure 4, and which surrounds a short shaft 28. This shaft being rigidly affixed to the angular members 25, serves to maintain these members in parallel planes.

The pumping unit is actuated by a suitable source of power, not shown, which is attached to the reduction unit 29, through which the arm 30 is rotated. This arm is weighted by weights 31, 5 and is connected to the beam 10 by the pitman arm 32.

A member 32^a is formed as shown in Figure 7, and is welded to the upper end of the arm 32. The upper part of the member 32^a is secured to a block 33, which is affixed to a roller 34. This roller rests in a bearing 35 which has a concave recess and is surrounded by a box 36, the roller 34 being retained in position by a shaft 37. The box 36 is secured to the walking beam 10, and it will thus be seen that as the beam 10 is rocked, the roller 34 oscillates in its recess in the bearing 35. The assembly is protected against ingress of moisture and dust by a hood or cover 38 which is secured to the member 32^a.

20 The pump rod assembly is attached to the depending members 39 which surround a member 40, comparable to the conventional "horse-head". The members 39 are preferably suspended by means of a suspension bearing similar to the one 25 above described, and illustrated in Figures 7 and 8, the assembly being protected by a hood 41.

The position of the beam 10 and its supporting structure at the midpoint of the stroke is illustrated in Figure 1. In this position the supporting beams 5 are in a vertical position and the articulate leg, comprised of the link 24 and the angular members 25, is in the position shown. When, however, the beam 10 is rocked to the position illustrated in Figure 6, the supporting members 5 are constrained to move to the position shown, that is with their upper ends moved arcuately forward toward the well. Since the beam 10 is hinged to the upper ends of the members 5, it is moved forward as it is rocked, thereby maintaining the members 39 directly over the well and effecting a straight lift on the pump rods. During this movement, the forward or articulated member is also displaced, since the shaft 28 is constrained to move in an arc with the length of the link 24 as a radius. The beam 10 is also displaced forwardly when it is rocked to the bottom of the stroke, thereby constraining the pump rod assembly to move in a perpendicular path throughout the stroke.

50 When it is desired to service the well, and hence becomes necessary to move the beam to a position where it will not interfere with the servicing operation, the unit is first disconnected from the pump rods and the bolts 20 are then removed. Sections of pipe are then placed over the lugs 23 and the support 16 is swung backward from the well around the shaft 14. This movement causes the beam 10 to move to a position where it will not interfere with the servicing operation. If desired, the arm 30 may be disconnected from the gear box to facilitate the movement of the beam 10 and its supporting members.

55 The slots 1^a in the beams 1 provide a means for shifting the base of the uprights 5. Thus, for example, should it be found desirable to impose a greater part of the load on the articulate member than is present when the beam 10 is horizontal and the members 5 are vertical, the bearings 3 may be shifted rearwardly along the beam 1 in the slots 1^a.

70 Figure 10 illustrates a modification of the invention with the principle applied to a pump jack. A pair of base members 42 each carry a bearing block 43 between which blocks a shaft 44 is positioned. This shaft is free to rock in the

bearings 43 and has a pair of upright beams 45 attached thereto. A shaft 46 is carried by the upper ends of the beams 45, on which shaft the walking beam 46 is hingedly mounted. The forward end of the walking beam 46 is provided with 5 the member 47 from which the depending members 48 are suspended. The forward ends of the beams 42 carry the shaft supports 49 between which a shaft 50 is secured. A support 51 is mounted on the shaft 50 and normally bolted to 10 cross members between the base beams 42. The structure just described is identical to that of the corresponding structure of the pumping unit principally illustrated by Figures 1, 2 and 6. It will be noted however that the upright members 15 45 are not provided with cross bracing, such as the plates 6 between the uprights 5.

In the pump jack illustrated in Figure 10, the supporting structure is replaced by the structure shown, which is comprised of a pair of V shaped 20 members 52, rigidly attached to the beam 46 and provided with the braces 53, and the beam 54 which is arranged in a manner similar to the beam 24 of the pumping unit. The beam 54 is positioned between a shaft 55, carried between 25 the braces 53, and a shaft 56 carried by the supporting member 51. A pair of beams 56 and 57 are positioned on opposite sides of the beam 54 and are hingedly mounted on a shaft 58 which latter is rigidly mounted between the V members 30 52. The members 56 and 57 extend to a point past the well, where they are interconnected and attached to a conventional pull rod. Since the shafts 44, 46, 55, and 56 are arranged in a manner identical with that of the shafts 4, 9, 28, and 35 21 of the pumping unit first described, it will be seen that the beam 46 is constrained to move in the same manner as the walking beam 10, that is with its members 48 at all times in a perpendicular path.

40 Manifestly, the construction as shown and described is capable of some modification and such modification as may be construed within the scope and meaning of the appended claims is also considered to be within the spirit and intent of 45 the invention.

What is claimed is:

1. A straight lift well pump including a base and a walking beam, a pair of supports hinged to 50 said base and to said walking beam, and an articulated leg, said leg comprising a structure rigid with respect to said walking beam and depending therefrom, and a link hinged adjacent said base and likewise hinged to said depending structure.

2. A straight lift pumping unit including a base 55 and a walking beam, a tripod supporting structure interposed between said base and said walking beam, said tripod comprising a pair of supports hinged to said base and to said walking beam and an articulated leg, said leg including 60 a pair of V shaped members rigidly attached to said walking beam, and a link hinged to said V-shaped members and likewise hinged adjacent said base, and a pitman for actuating said walking beam.

3. A straight lift pump jack including a base and a walking beam, a pair of supports hinged to 65 said base and to said walking beam, an articulated supporting structure including a frame depending from said walking beam, a link hinged to said depending frame and to said base, and means attached to said frame for actuating said pump jack.

4. A straight lift well pump including a base and a walking beam, a pair of supports hinged to 70

75 said base and to said walking beam, an articulated supporting structure including a frame depending from said walking beam, a link hinged to said depending frame and to said base, and means attached to said frame for actuating said pump jack.

5 said base and to said walking beam, and an articulated leg, said leg comprising a structure rigid with respect to said walking beam and depending therefrom, a link hinged to adjacent said base and likewise hinged to said depending structure, and means whereby said walking beam may be inoperatively displaced relative to the well.

6. A straight lift pumping unit including a base and a walking beam, a tripod supporting structure interposed between said base and said walking beam, said tripod comprising a pair of supports hinged to said base and to said walking beam and an articulated leg, said leg including a pair of V shaped members rigidly attached to 10 said walking beam, and a link hinged to said V shaped members and likewise hinged adjacent said base, a pitman for actuating said walking beam, and means connected to said articulated leg whereby said walking beam may be inoperatively displaced relative to said base.

7. In a well pumping apparatus a base and a walking beam, a supporting tripod for said walking beam including a pair of interconnected supports hinged to said base and to said walking beam and an articulated leg, said leg comprising a member rigid with said walking beam and a link hinged to said base and to said latter member at a point below said walking beam.

8. A straight lift pumping apparatus for wells including a base and a walking beam, a tripod supporting said beam on said base, two of the legs of said tripod having hinged connections with said walking beam and said base and the third leg of said tripod comprising a link hinged 30 to said base and likewise hinged at its upper end

5 to a structure rigid with said walking beam, and means whereby the base of said articulated leg may be shifted in position to move said walking beam to an inoperative position relative to the well.

9. A straight lift pumping unit including a walking beam and a base, a supporting member for said walking beam pivoted at its ends to said base and walking beam, a pair of relatively angular members connected to said walking beam, 10 a link pivotally joining said members to said base whereby the pivotal points thereof will be substantially aligned with the upper pivotal point of said supporting member when said walking beam is horizontal.

10. A straight lift pumping unit including a walking beam and a base, a supporting member for said walking beam pivoted at its ends to said base and walking beam, means connected to said walking beam and having a link joining the same 20 pivotally to said base whereby the pivotal points thereof will be substantially aligned with the upper pivotal point of said supporting member when said walking beam is horizontal and means for displacing the lower pivotal point of said link. 25

11. A pumping apparatus including a walking beam and a base, a supporting member pivoted at either end to said base and walking beam, a member rigidly connected to said walking beam and depending therefrom and affording a connection for a pull rod at its lower extremity, and means providing a pivotal connection between said base and an intermediate point between the upper and lower extremities of said rigid member.

GEORGE T. HUMPHREY. 35
